Attorney.

UNITED STATES PATENT OFFICE

HENRY J. KAISER, OF EVERETT, WASHINGTON.

PAVEMENT.

1,234,171.

Specification of Letters Patent. Patented July 24, 1917.

Application filed January 24, 1917. Serial No. 144,284.

To all whom it may concern:

Be it known that I, HENRY J. KAISER, a citizen of the United States, residing at Everett, in the county of Snohomish and State of Washington, have invented a new and useful Improvement in Pavements, of which the following is a specification.

This invention relates to certain new and useful improvements in pavements for streets and roads.

One of the important objects of the present invention is to so simplify the construction of pavements as to reduce the cost of repairs to the minimum.

Those experienced in the construction and maintenance of streets and roads know that one of the most important factors connected therewith, which is emphasized more and more each succeeding year is that of cost of maintenance, and it has been demonstrated beyond question that the cost of repairs can only be reduced by improving the construction.

The travel on streets and roads is increasing amazingly, both in volume and weight, and advanced engineering methods are sought and employed in the construction of highways and many problems are being solved by that inexorable teacher—experience—and one of the most important is the construction of roads that will stand up under the immense traffic that is now imposed upon them. Aside from the traffic on the pavements they are subject to the changing temperatures, which is a phase to be considered in the construction work.

In order to overcome some of the ills mentioned and thereby reduce the cost of maintenance, I have devised a pavement consisting of two independent layers of concrete with a thin layer of oil or other suitable lubricant therebetween.

The invention comprises the novel features of construction which will be herein-after described and particularly pointed out in the claims concluding this specification.

In the accompanying drawings, forming part of this specification, is shown the preferred embodiment of my present invention.

Figure 1 is a vertical cross section on line $x-x$ in Fig. 2.

Fig. 2 is a top view of a longitudinal fragment.

Fig. 3 is a vertical cross section of expansion joint with angle irons attached. 55

Same letters refer to similar parts throughout the several views.

In carrying out my invention I first prepare the foundation or what may be termed "the bed", to receive the concrete pavement, 60 for with whatever care the pavement may be laid it is very apt to be a failure unless the foundation is good and dependable. It is just as important a factor in road building as in any other work of construction, 65 and while it is true that concrete properly made and laid has great inherent strength it gives much better service and needs less attention if it be laid upon a firm, unyielding bed having a smooth, level surface. 70

Having such a foundation I lay thereon, and thoroughly ram, a concrete base A varying in thickness from two to eight inches, of a rather lean mixture, bringing the top to a smooth, even surface by means of a float, 75 trowel or the like.

No expansion joints are placed in this primary layer so that it may be denominated monolithic in character as it is continuous and unbroken. 80

After this primary layer of concrete has thoroughly set and hardened there is applied to the surface thereof a sheet of oil (crude or heavy) or other suitable lubricant, B, especial care being exercised to secure a 85 uniform even distribution thereof over the entire surface.

Upon this sheet of oil is placed a layer of paper of suitable thickness, C, to cover completely the sheet of oil, thereby preventing 90 and separating, during the process of construction, the secondary layer or wearing surface from direct contact with the oil and primary labor.

Immediately following the positioning of 95 the paper in the manner mentioned, the secondary layer of concrete as the wearing surface, D, is superposed on the paper to a depth varying from two to eight inches; for this purpose a richer mixture may be 100 used. The surface of this secondary layer or wearing surface is finished smooth and level by means of a float or the like.

In superposing the secondary layer or wearing surface as described, expansion 105 joints, E, are placed equidistant, and in

order to prevent the joints from rising and thereby allow the contiguous sections to unite at their lower edges under the joint, there are attached to the lower edge of the 5 expansion joint light weight angle-irons, G, at from five to twenty feet apart so that the concrete is delivered onto the angle-irons at the base of the joint, thereby holding the joint in place and securing a water-tight 10 joint.

When contiguous sections of the pavement unite beneath the expansion joint, much of the benefit for which the expansion joint is made is lost for the pavement has 15 not the same freedom of movement on the base upon which it rests as it otherwise would, and hence the cause of cracks forming at expansion joints at a change in temperature.

20 The secondary layer or wearing surface may be reinforced by embedding therein meshed iron or other suitable material.

It will be noted that the expansion joints provided for in the secondary layer or 25 wearing surface are confined to the said layer which makes said layer independent of the base on which it rests so far as its sliding thereon is concerned, which freedom of movement is far greater than can possibly

30 be provided in any pavement that consists of only one layer of concrete, and consequently the cracking of pavement made according to this invention is reduced to the minimum.

35 As the expansion joints under this invention extend through the secondary layer only, there is no opportunity for seepage of water through said joints to the roadbed and softening same which is a frequent

40 cause of much injury to pavements as ordinarily laid; and further, under this invention fewer expansion joints are required.

A pavement constructed as herein shown and described reduces the cost of maintenance 45 very materially, for even if cracks do develop in the wearing surface the depth of the crack is restricted to the depth of said wearing surface; and water can not seep therethrough to the roadbed for it is prevented first, by the paper, and second, 50 by the oil, and third, by the primary layer of concrete beneath the oil.

Owing to the bottom course being of concrete it allows the top course to be laid more 55 uniform by preventing the wet top concrete course from penetrating or leaking into the base, as in the case of earth or other porous subgrade.

I claim as my invention:—

60 1. A pavement composed of two independent layers of concrete, the primary layer resting upon a suitable roadbed and a

second layer superposed on the primary layer with a sheet of oil or other suitable lubricant therebetween.

2. A pavement composed of two independent layers of concrete, the primary layer resting upon a suitable roadbed, and an upper secondary layer as a wearing surface, and a sheet of oil therebetween.

3. A pavement composed of two independent layers of concrete, the primary layer resting upon a suitable roadbed, and an upper secondary layer as a wearing surface, and a sheet of oil and a layer of paper therebetween.

4. A pavement composed of two independent layers of concrete, the primary layer resting upon a suitable roadbed, an upper secondary layer as a wearing surface 80 with reinforcing means embedded therein, and a sheet of oil and a layer of paper therebetween.

5. A pavement composed of two independent layers of concrete, the primary layer resting upon a suitable roadbed, an upper secondary layer as a wearing surface, a sheet of oil and a layer of paper therebetween, and expansion joints extending from the top of the wearing surface to the paper 90 beneath.

6. A pavement comprising a suitable roadbed, a primary layer of concrete compacted directly on said roadbed, a sheet of oil applied to the surface of said primary layer, a layer of paper of suitable thickness covering the sheet of oil, a crust of concrete superposed on the paper and having reinforcing means embedded therein, and expansion joints extending from the top of the 100 wearing surface to the paper beneath.

7. A pavement composed of two independent layers of concrete, the primary layer resting upon a suitable roadbed, an upper secondary layer as a wearing surface, a sheet of oil and a layer of paper therebetween, and expansion joints extending from the top of the wearing surface to the paper beneath and provided with angle-irons at their lower edges.

8. A pavement comprising a suitable subgrade, a primary layer of concrete supported directly upon said subgrade, a sheet of oil applied to the surface of said primary layer, a layer of relatively tough paper of suitable thickness covering the sheet of oil, a crust of concrete superposed on the paper as a wearing surface, and expansion joints dividing said wearing surface into sections adjacent to each other, said expansion 115 joints extending from the top of the wearing surface to the paper beneath.

HENRY J. KAISER.
